[57] CLAIM

The ornamental design for a paint can holder for ladders, as shown.

DESCRIPTION

FIG. 1 is a right perspective view of a paint can holder for ladders embodying my new design;

FIG. 2 is a top plan thereof;

FIG. 3 is a bottom plan view thereof;

FIG. 4 is a right side elevation thereof;

FIG. 5 is a left side elevation thereof;

FIG. 6 is a front elevation thereof; and

FIG. 7 is a rear elevation thereof.
